UNITED STATES PATENT OFFICE.

THOMAS F. TOMLINSON, OF LAMBERTS POINT, VIRGINIA.

SUPPORTING-BRACKET FOR BRAKE-SHOES.

1,209,232

Specification of Letters Patent. Patented Dec. 19, 1916.

Application filed May 9, 1916. Serial No. 96,417.

To all whom it may concern:

Be it known that I, THOMAS F. TOMLINSON, a citizen of the United States, residing at Lamberts Point, in the county of Norfolk 5 and State of Virginia, have invented certain new and useful Improvements in Supporting-Brackets for Brake-Shoes, of which the following is a specification.

This invention relates to supporting 10 brackets for rolling stock brake shoes, the principal object being to provide a combined bracket and spring plate which is expeditiously attachable with and detachable from the spring plank of the truck frame.

Another object is to provide a unit which 15 is integrally cast and may or may not be equipped with a spring seat, but will be found to be equally efficient in the capacity specified.

Other objects as well as the nature, characteristic features and scope of my invention will be more readily understood from the following description, taken in connection with the accompanying drawings, and 25 set forth in the claims appended hereto.

Figure 1 is an end elevational view partly in section of my improved supporting bracket illustrating the application of the same. Fig. 2 is a top plan view of the 30 bracket. Fig. 3 is a side elevational view of the same. Fig. 4 is a top plan view of a modified form, and Fig. 5 is a side view of the modification shown in Fig. 4.

In the drawings the supporting bracket is 35 generally designated 1 and in this instance comprises a body which is of a substantially U-shaped configuration in cross section so as to conform to the contour of the spring plank 2 which is used in this invention. 40 The body 1 is of an elongated, preferably oblong configuration, and is equipped on its upper face with a plurality of studs 3 which are adapted to have encircled thereabout, the usual coil springs used for supporting the truck bolster. It is to be understood that 45 one of the brackets is to be carried in each end of the spring plank 2, and as shown to advantage, by the cross section in Fig. 1, the studded end of the body will extend 50 toward the free terminal of the plank.

An enlargement 4 is formed on the upper face of the body, and has a plurality of spaced lugs arranged in pairs thereon, which project laterally beyond the body 1 and spring plank 2 as illustrated to advantage in Fig. 1. An opening 6 is arranged trans-

versely through the body 1 and is adapted to receive a bolt or other securing means therein, in order to retain the body from casual displacement on the plank 2. 60

As illustrated in Fig. 1, the ears 5 are adapted for pivotal engagement with the levers 7 of the brake shoes and will prove an efficient means for permitting expeditious removal of the shoes when so desired, without interfering with any other portion of the truck frame. 65

In Figs. 4 and 5 a slight modification of the invention has been shown, in which a body 8 is provided, which has openings 9 70 formed therein adapted for the reception of a securing means, by which the body is fixedly engaged with the spring plank 2. This will eliminate the use of the supporting seat for the spring which is shown in 75 Figs. 1, 2 and 3, since it may be desirable to associate the bracket with the spring plank, subsequent to associating the bolster springs, etc., therewith. Ears 10 are projected laterally from one of the terminals of the body 8 and are adapted to serve in the same capacity as Figs. 1, 2 and 3. A reinforcing rib 11 is formed on the upper face of the body 8 and engages with a side wall 12 which connects the ears 10 to the body 9. 80

It will be understood that the above description and accompanying drawings comprehend only the general and preferred embodiment of my invention and that various minor changes in details of construction, 90 proportion and arrangement of parts may be made within the scope of the appended claims and without sacrificing any of the advantages of my invention.

Having thus fully described my invention, 95 what I claim as new and desire to secure by Letters Patent is:—

1. A brake shoe bracket including an integral casting consisting of an anchoring portion adapted for securement to the truck 100 frame, and ears projecting above and laterally beyond the portion of the frame upon which said body is mounted for engagement with the brake levers.

2. A brake shoe bracket including, in combination with a spring plank U-shaped in cross section, an inverted U-shaped body mounted on said plank and provided with an enlargement on its upper face with ears 110 projecting therefrom, for pivotal connection with the brake shoe.

3. A brake shoe bracket including a body

for engagement with the truck frame, studs formed on the upper face of one end of the bracket to receive the bolster springs thereabout, an enlargement formed on the upper 5 face of the opposite end of said body having portions extending laterally therefrom to provide spaced ears for pivotal connection with the brake shoe levers for suspending

the latter in proximity to the wheels of the truck frame.

10

In testimony whereof I affix my signature in presence of two witnesses.

THOMAS F. TOMLINSON.
